UNITED STATES PATENT OFFICE.

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed July 7, 1922. Serial No. 573,353.

This invention relates to fastening inserting machines and is herein illustrated as embodied in a machine particularly designed to insert metallic fastenings such as nails into trunks or other bulky objects during the manufacture thereof.

Many trunks as manufactured at the present time consist of wooden boxes covered on the outside with a heavy fabric or other sheet material and reinforced at the edges and at intervals across the surfaces of the trunks with strips of metal, fibreboard, wood, or other suitable strengthening material. These reinforcing strips are ordinarily secured in place by stout nails more or less closely spaced and, prior to the present invention, usually inserted by hand.

Accordingly it is an object of the present invention to provide a machine particularly adapted to insert fastenings into trunks and the like during the manufacture thereof.

With this object in view and in order to speed up the insertion of the fastenings, a feature of the invention comprises the combination in a fastening inserting machine having fastening inserting mechanism and a co-operating work support, of means for operating the fastening inserting mechanism to insert fastenings in the work during relative movement of the fastening inserting mechanism and the support transversely of the work. In the illustrated machine the work is held stationary on the work support and the throat and driver are carried by a head which is moved continuously across the work, the fastenings being inserted in a row during the continuous movement of the head.

A further feature of the invention comprises the provision in a fastening inserting machine in which the head of the machine and the work have continuous relative movement in a direction transversely of the work, of means for moving the nozzle or other device by which the fastenings are guided to the work in a direction opposite to that of the relative movement of the head and the work so that this relative movement is counteracted at the instant of the insertion of each fastening with the result that the fastening is driven just as it would be if the head of the machine and the work were both at rest. In the illustrated ma-

chine the fastening inserting instrumentalities are carried by a swinging head mounted upon a head arranged for continuous movement at a uniform speed transversely of the work, the linear velocity of the outlet of the nozzle carried by the swinging head, relatively to the continuously moving head, being, at the time the fastenings are inserted, equal to the velocity of the continuously moving head but in the opposite direction thereto.

A further feature of the invention comprises the provision in a machine arranged to insert fastenings in trunks or other bulky objects and having means for causing relative movement of the fastening inserting instrumentalities and the work, in a direction transversely of the work, of gear shift mechanism arranged to vary the rate of relative movement of the head of the machine and the work and thus to vary the spacing of the fastenings inserted into the work. In the illustrated machine the varying of the speed of movement of the head in no way affects the speed at which the fastening inserting mechanism is operated or the number of operations which it performs in a given unit of time so that the distance between adjacent fastenings varies directly with the rate of movement of the head relatively to the work.

In accordance with a further feature of the invention, the illustrated machine comprises a novel organization of fastening inserting mechanism and co-operating work presenting and supporting means.

Still other features of the invention include the provision of novel stop mechanism and reversing mechanism to cause the head of the machine to stop and to reverse its direction of movement when it reaches predetermined points in its path of movement across the work.

Still another feature of the invention comprises a gage and mechanism for rapidly and conveniently shifting the gage from one to the other of two positions upon opposite sides of the point at which the operating devices of the machine act upon the work so that the work may conveniently be presented to the machine for operation, for example, upon the two surfaces of a dihedral angle of the work and at predeter-

mined distances from the edge at which those surfaces intersect.

With the above and other objects and features in view the invention will now be described in connection with the accompanying drawings which illustrate a practical exemplification thereof and pointed out in the subjoined claims.

Fig. 1 is a side elevation of a trunk nail-
10 ing machine illustrating an embodiment of the present invention, and provided with two work supports arranged so that one or the other may be utilized to present the work for the insertion of fastenings adjacent to any of the edges or corners of a trunk;

Fig. 2 is a side elevation of a trunk nail-
15 ing machine provided with a single work support arranged to enter the dihedral angle between an end and the back or front of the body or cover of a trunk to support the body or cover for the insertion of fastenings;

Fig. 3 is a front view and Fig. 4 is a
20 side elevation of the head of the machine of Fig. 1, certain parts of the machine being shown in cross-section in Fig. 4;

Fig. 5 is a side elevation, partly broken away, of clutch mechanism, a gear shift, and
25 other co-operating parts for transmitting power to the traveling head of the machine;

Fig. 6 is a transverse section of the lower portion of the machine, partly broken away, and illustrating more particularly the construction of a work support arranged to enter the dihedral angle between the bottom and side or end of the body of a trunk or the top and side or end of the cover of a trunk;

Fig. 7 is a view on a larger scale than Fig.
30 6 illustrating means for raising and lowering the work support of that figure;

Figs. 8 and 9 are a side and an end elevation, respectively, with parts broken away, of certain gage shifting and adjusting mechanism used to facilitate the insertion of fastenings in rows located at predetermined distances from the line of intersection of adjacent side and end surfaces of a trunk;

Figs. 10 and 11 are end and front elevations, respectively, of gage adjusting and locking means arranged to adjust and hold the gage for the insertion of fastenings adjacent to the line of intersection of the bottom and side or end of the body of a trunk or of the top and side or end of the cover of the trunk; and

Fig. 12 illustrates in cross-section the manner in which staples, instead of nails, may be conducted from the hopper to the point of fastening insertion of the machine.

The illustrated machine is of that type in which the work remains stationary upon a work support while the fastening inserting instrumentalities traverse the work inserting fastenings as they go.

As illustrated in Figs. 1 and 3 to 11 inclusive, the machine is provided with a main frame comprising a pair of columns 20, 22, connected near their bases by a web 24 and at their upper extremities by a track member 26 upon which is slidably mounted the head 28 of the machine. A rack 30 is carried by the frame parallel with or formed as a part of track 26. A series of power driven shafts 32, 34 and 36 (Figs. 1, 3 and 4) are journaled in suitable bearings in the frame, also parallel with track 26.

The head 28 of the machine is provided with a nail pot or hopper 38 (Fig. 3) and a raceway 40 having a cover 41 of any suitable or usual construction. As illustrated the nail pot is mounted upon a shaft 39 being rotated thereon by power derived from shaft 32 through a suitable train of gearing. For this purpose a pulley 42 is slidably mounted upon the shaft 32, the shaft and the bore of the pulley being of a configuration to cause the pulley to rotate with the shaft. The hub of pulley 42 is journaled in bearing members 44 carried by a rod 46 (Figs. 3 and 4) extending upwardly and rearwardly upon the head 28. A belt 48 connects pulley 42 with a pulley 50 secured to a shaft 52 suitably journaled in head 28 and provided with a spiral gear 54 meshing with a co-operating spiral gear 56 mounted upon a shaft 58, the rear extremity of which carries a pinion meshing with spur gearing 60 formed about the periphery of the nail pot. Shaft 52 carries upon its right hand extremity (Fig. 3) a cam co-operating with a blade 62 secured at 64 to a lever 66, the blade 62 being held in contact with its cam by a torsion spring 68. Lever 66 also carries a spring held finger 70 which is thus oscillated by the rotation of the cam and serves to vibrate the raceway to assist the feed of the nails therein.

A throat or nozzle made up of a pair of resilient or resiliently supported members 74 with their lower nail retaining ends arranged to separate as the head of a nail is forced therebetween, and a driver 76 as well as parts of the operating mechanism therefor are carried upon a swinging head 78 mounted upon the sliding head 28 for movement therewith lengthwise of track 26. A pair of brackets 80 operate as guides to hold the swinging head 78 in place during its swinging movement.

Journaled in the head 28 is a cam shaft 84 driven from shaft 34 through a pair of bevel gears 86, 88, the former of which is splined to shaft 34. Fast upon shaft 84 is a cam 90 provided with a cam track in which operates a roll 92 carried by one end of a lever 94, the latter in turn being carried by a rock shaft 96 provided with a slotted arm 98 in which is adjustably mounted one end of a link 100, the other end of which is piv-

oted at 102 to the swinging head 78 so that each rotation of shaft 84 causes a complete oscillation of the swinging head.

Slidinely mounted in ways 104 carried by the swinging head 78 is a block 106 to which is adjustably clamped a driver bar 108, the latter having the driver 76 secured to its lower end and being provided with operating mechanism substantially as disclosed in U. S. patent to Louis Goddu No. 490,624, Jan. 24, 1893. Thus the driver is elevated periodically by the operation of a cam mounted upon shaft 84 and is driven down to insert the fastenings by spring 110, the latter being connected to the driver bar through lever 112 and link 114.

To control the passage of the nails from the raceway 40 to the throat member 74, the machine is provided with a separator 120 carried at the lower extremity of a lever 122 (Fig. 3) pivoted at 124 to the swinging head 78 and carrying at its upper end a roll 126 co-operating with a cam track formed upon cam 90, roll 126 being held in contact with the cam track by a spring 128. Thus the separator is operated synchronously with the movement of the throat and with the operation of the driver to cause the delivery of a fastening from the raceway to the throat when the throat is at the right hand extremity of its path of movement, as viewed in Fig. 3, and before descent of the driver to insert the fastenings.

In order to speed up the operation of the machine as a whole, the sliding head 28 is arranged for continuous movement along track 26. To facilitate the insertion of fastenings in the work during the actual movement of the sliding head, the swinging head of the machine is arranged so that at the time of the actual insertion of each fastening, that is during substantially that portion of the descent of the driver when it is in contact with the head of a fastening, the swinging head is moving relatively to the sliding head in the opposite direction from the movement of the sliding head and at such an angular velocity that the linear velocity of the throat with respect to the sliding head is equal in extent but opposite in direction to the velocity of movement of the sliding head. Thus though the sliding head continues without interruption in its traversing movement across the work, the fastening is inserted substantially as it would be if the entire fastening inserting mechanism and the work were both at rest, the swinging movement of the head 78 counteracting the sliding movement of head 28.

Power for shifting the sliding head 28 along track 26 is transmitted from shaft 36 by means of gearing which will now be described. A pinion 134 formed integral with a bevel gear 136 is fast on a shaft 138 carried by sliding head 28 and meshes with rack

30. Co-operating with bevel gear 136 is a second bevel gear 140 mounted for rotation upon shaft 36 and arranged to be driven thereby through co-operating clutch members 142, 144 carried by bevel gear 140 and 70 by a sleeve 145 respectively, the latter being splined to shaft 36 and being formed with a groove co-operating with a yoke 146 carried by a rack 148 slidinely mounted in the head 28. Rack 148 meshes with a gear member 75 formed rigid with a lever 150 so that the rocking of the lever in one direction or the other will throw clutch members 142, 144 into or out of operative relation. When the clutch 142, 144 is thus rendered inoperative, a weight 154 carried in a bite of a chain or cable 156 anchored at one end to the frame of the machine and at the other end to head 28 returns the latter to the left 80 for the commencement of a new row of fastenings. A limit stop 155, preferably adjustable, may also be provided positively to limit the movement of head 28 to the left when it is returned by weight 154.

Lever 150 may conveniently be provided 90 with a pair of notches 160 arranged to co-operate with a resilient or spring mounted latch member 161 impositively to hold clutch members 142 and 144 in or out of engagement during the movement of the head of 95 the machine.

As illustrated in Figs. 3 and 4, shaft 138 may conveniently be provided with a hand wheel by means of which the sliding head 100 may be moved manually along the track.

The operating mechanism for shafts 32, 34 and 36 will now be described. Carried by a bracket 170 (Fig. 1) attached to column 20 is a motor 172 suitably belted to a pulley 174 (Fig. 5) loose upon a shaft 176 105 journaled in a change speed gear casing 178 carried by the frame of the machine. Shaft 176 is a continuation of, or is operatively connected to, shaft 34 so that the two rotate together. Pulley 174 is formed with a clutch 110 surface arranged for engagement with a co-operating surface of a clutch member 178, the latter being splined to shaft 176 and provided also with a brake surface 180 arranged to co-operate with a stationary brake surface 115 so that shaft 176 may be brought to rest immediately when clutch member 178 is thrown out of driving relation to pulley 174. A stiff compression spring 182 tends to move clutch member 180 into driving relation with pulley 174. Carried by the hub 120 of clutch member 178 are a pair of pins 184 engaging a pair of hook members formed upon the upper end of a lever 186 fulcrumed at 188 to a suitable rigid part of the frame. At its lower end lever 186 is connected to one 125 end of a toggle member 189, the other end of which is connected to a co-operating toggle member 190 pivoted at 192 to a lever 194 fulcrumed at 196 to a stationary part of 130

- the frame. At its upper extremity lever 194 is provided with a cam roll 198 co-operating with a cam track 200 formed upon a cam member carried by shaft 176. Cam track 200 is provided with a rise 202 of such a configuration that when toggle 188, 190 is straightened it will rock lever 194 to an extent sufficient to cause lever 186 to compress spring 182 and move clutch member 178 out of engagement with pulley 174 and into engagement with brake surface 180 to stop the rotation of shaft 176. When, however, toggle 188, 190 is broken the passage of rise 202 past cam roll 198 has no effect at all upon lever 186 or the clutch member.
- Pivoted at 204 to toggle member 190 is a latch lever 206 provided with a block 208 arranged to co-operate with a lug 210 formed upon toggle member 188. A compression spring 212 surrounding a rod 214 and bearing at one end against the frame of the machine and at the other end upon a collar carried by the rod tends to straighten the toggle, and when it is once straightened block 208 bearing against lug 210 holds it positively in that condition until the left hand end of lever 206 is swung downwardly as will be hereinafter described.
- To permit the operative conveniently to stop and start the machine from any position in front of it, there is provided a controlling rod 216 (Figs. 1 and 5), upon which is adjustably mounted a stop 218 arranged in the path of movement of a finger 220 carried by the head 28 of the machine. Rod 216 is pivoted at its left hand end to a bell crank lever 222 fulcrumed to a lug or projection 224 carried by the frame of the machine. Bell crank lever 222 is connected by a pin-and-slot connection to a link 226 pivoted at its other extremity to lever 206. Thus when rod 216 is shifted to the left, bell crank lever 222 pulls down upon link 226 and lever 206, compressing springs 212 and breaking toggle 188, 190 so that spring 182 is permitted to throw clutch 180 into operation. On the other hand, when rod 216 is shifted to the right, lever 206 is permitted to rise under the action of compression spring 212 straightening the toggle, which is latched in straightened position by the co-operation of block 208 and lug 210, so that when the rise 202 of cam track 200 reaches cam roll 198, the straightened toggle will rock lever 186 in a clockwise direction compressing spring 182 and shifting clutch member 178 from operative to braking position. In order to hold rod 216 in the position to which it is shifted, bell crank lever 222 is provided with a pair of notches co-operating with a spring pressed latch member 228 which impositively holds it in position. When, during the traverse of head 28, finger 220 reaches stop 218, rod 216 is moved to the right, thus automatically ren-

dering the clutch inoperative and stopping the machine.

Journalized in the change speed gear box 178 is a squared shaft 240 upon which is rigidly mounted a large spur gear 242 meshing with a smaller spur gear 244 fast upon shaft 176. Slidably mounted on squared shaft 240 in a yoke 246 is a spur gear 248 meshing with a gear 250, the yoke being shiftable to bring gear 250 into mesh with any one of the sections of a cone gear 252 mounted upon the left hand end of shaft 36. Yoke 246 may be shifted by means of a hand lever 254 provided with a detent 256 operable through a spring-pressed grip 258 and co-operating with any one of a series of holes 260 to hold the gear 250 in meshing relation with any one of the gear members of the cone gear 252. Thus the speed of rotation of shaft 36 and hence the velocity of traversing movement of head 28 may be varied without changing the speed of rotation of shaft 34 or of shaft 176, or the rate of insertion of the fastenings, the spacing of the fastenings in the work being correspondingly varied.

Rigid with pulley 174 and hence continuously rotated therewith is a smaller pulley 270 belted to pulley 272 loosely mounted upon shaft 32 and having a bearing in a bracket member carried by the frame. Splined to shaft 32 is a sleeve 276 carrying at its left hand end a clutch member 278 co-operating with a clutch surface 280 formed upon pulley 272, clutch member 278 being separated from the hub of the pulley by a spring washer 282. Normally contacting with the right hand end of sleeve 276 is a disk 284 engaging a pair of lugs 286 carried by a yoke 288 mounted upon the end of a shaft 290 suitably journalized in the frame of the machine, and provided with a handle 292 for the operation thereof. A spring 294 holds disk 284 in engagement with lugs 286, the spring bearing at its right hand end upon a collar 296 fast upon shaft 32.

Lugs 286 are so arranged that when handle 292 is moved to its extreme right hand position they are rotated slightly past their extreme right hand position so that spring 294 is compressed and clutch member 278 is rendered inoperative. When handle 292 is moved to its extreme left hand position, lugs 286 are moved far enough to the left to permit spring 294 to force clutch member 278 into engagement with clutch surface 280 to cause the rotation of shaft 32. It will be evident from the foregoing that shaft 32 and consequently the hopper mechanism 123 may be operated continuously whether the traversing and fastening inserting mechanisms are in operation or not, thus assuring a continuous supply of nails in the raceway. On the other hand, the hopper operating 130

mechanism may be thrown out of operation while the rest of the machine continues running as may be convenient, for example, in emptying the raceway.

5 The machine of Fig. 1 is provided with two separate work supports 300 and 302, the former being arranged to support the body or top of a trunk while fastenings are inserted adjacent to an edge between the top 10 or bottom and the side or end, while the latter is arranged to support the body or top of a trunk during the insertion of a row of fastenings along an edge adjacent to a side and end.

15 Work support 300 comprises a head illustrated as a bar or anvil 304 (Fig. 6) arranged to enter a dihedral angle of the work and carried upon the upper extremity of a pair of arms illustrated as rods 306 each 20 having a bearing portion journaled in a bearing sleeve 308 provided with a downwardly extending arm 310. Sleeves 308 are mounted for rotation in vertical planes about a shaft 312, the latter being journaled in a 25 pair of slidably mounted boxes 314. Web 24 is provided with a pair of upwardly extending lugs 316 which serve as stops for arms 310, springs 318 tending to hold arms 310 and lugs 316 in contact. Each rod 306 30 is provided with a counterweight 320 acting in opposition to spring 318 but preferably of a weight not quite sufficient to overcome the action of the spring. This work support may be lowered for the placing of 35 a trunk thereon and raised into operative position by mechanism which will now be described. Fulcrumed at 322 to the base of the columns 20, 22 is an elongated treadle 324, the rearwardly and upwardly extending ends of which are connected by adjustable links 326 with the knuckles of toggles 328, 330, the lower members of which are pivoted to web 24, and the upper members of which have bearings in slides 332 (Figs. 40 45 and 7) vertically movable in ways 334 carried by columns 20 and 22. Each slide 332 is provided at its upper extremity with a seat for a spring 336, the upper end of which bears against a nut 338 adjustable 50 upon a threaded rod 340 carried by box 314. Thus as the toggle is straightened shaft 312 and the work support carried thereby will be raised to bring the work into operative position, springs 336 yielding as may be 55 necessary. To insure the positive lowering of the work support when the treadle is released, each slide 332 carries a screw 342 arranged to impinge upon the upper end of box 314 as the slide is lowered, positively 60 to push box 314 down as the toggle is broken.

A supplemental work support illustrated as a vertically adjustable T-shaped bar 344 is carried by a web 346 connecting sleeves 308 and is at times convenient in supporting a

portion of the work remote from bar 304. 65

In order that the work support 300 may be utilized to support a trunk body or cover of any usual shape with either a top, bottom, side or end uppermost, rods 306 are bent as indicated in Fig. 6, being formed with 70 what is in that figure shown as an upwardly extending portion 348 and a forwardly extending portion 350, each rod being capable of rotation through 180° so that the formerly upwardly extending portion 348 extends 75 forwardly and the formerly forwardly extending portion 350 extends upwardly as shown in broken lines in Fig. 6. Since the bearings of anvil 304 on rods 350 are arranged in the line of the axes of bearing sleeves 308 about which rods 306 rotate, this may be done without removing the anvil. To facilitate this changing of position, each rod 306 is provided with a spiral gear 353 80 meshing with corresponding gears formed upon shaft 312 so that as the latter is rotated rods 306 will move from one position to the other. As shown in Fig. 1, a hand lever 352 is carried by shaft 312 to facilitate the rotation thereof. 90

The machine of Fig. 2 and the right hand end of the machine of Fig. 1 are illustrated as provided with a work support arranged to support a body or cover of a trunk for the insertion of fastenings adjacent to the corners between the sides and ends thereof, the work being positioned with its open face to the left. This work support comprises an outwardly extending arm 360 mounted for vertical sliding movement in ways illustrated as carried by a plate 362 secured to column 22. Attached to the left hand end of plate 360 is a downwardly extending sleeve 364 in which is slidably carried a knob 366 formed on the upper end of a rod 368, the lower end of which is screw-threaded and carries an abutment 370 for a compression spring 372 surrounding rod 368 and supporting sleeve 364 and plate 360. A pin 373 carried by knob 366 is positioned in a slot formed in sleeve 364, and limits the relative movement of rod 368 and plate 360. Rod 368 is in turn supported at its lower end by a lever 372 fulcrumed at 374 to column 22 and connected by a link 376 with the upwardly extending end of a treadle 378 fulcrumed at 380 to the base of column 22. The upwardly extending end of this treadle and link 376 co-operate to form a toggle which is provided with a spring 382 tending to break the toggle so as to permit the lowering of the work support when the treadle is released. When the treadle is depressed upon the other hand, the toggle is straightened and lever 372, rod 368, spring 372, sleeve 364 and plate 360 of the work support are raised so that the work is held yieldingly against a gage or abutment 384. 110 115 120 125

Abutment 384 and the corresponding abutment 386 which co-operates with the work support 300 are illustrated as adjustable gages arranged to facilitate the correct presentation of the work to the fastening inserting means. Accordingly abutment or gage 384 is carried by the forward extremity of a pair of rack bars 388, 390 slidably mounted in ways 392, 394 carried by the frame of the machine and meshing with gear segments 396, 398 fast upon an inclined rock shaft 400 (Figs. 8 and 9). In Fig. 9 gage 384 is shown in position to present a trunk for the insertion of nails in the position indicated at 402. If it is desired, however, to insert nails in the position indicated at 404, it is necessary to move gage 384 to the opposite side of the work support 302 from that which it now occupies, the work, of course, being rotated through an angle of 90°. With this in view means is provided for rocking shaft 400 so as to move the gage from one side to the other of the work support. Accordingly gear segment 396 is formed with a pair of concave seats 406, 408 arranged to co-operate with a pair of stops 410, 412 each secured for arcuate adjustment as by a bolt and slot connection 413 to a suitable part of the frame of the machine. Shaft 400 is provided with a handle 414 by which it may be rocked and with an arm 416 to which is anchored one end of a spring 418 the other end of which is anchored to the frame of the machine, the arrangement being such that as the handle 414 is rotated in a counter clockwise direction, as viewed in Fig. 9, the gear segments will be similarly rotated, shifting gage 384 to the right. As soon as shaft 400 has thus been rotated sufficiently to move the axis of spring 418 past the axis of shaft 400, the spring completes the rotation of the shaft, snapping seat 406 into engagement with stop 410.

As illustrated in Figs. 8 and 9, the work support 302 is provided with a readily removable nail clinching bar 430, the left hand extremity of which, as shown in Fig. 8, is formed with an opening 432 arranged to slip over a pin 434 to prevent upward or lateral movement of the bar while its other end is provided with an opening 436 arranged to receive the upper end of a spring-pressed plunger 438 to prevent endwise or lateral movement of the bar. Thus by manually depressing plunger 438 the clinching bar may conveniently be removed.

The abutment or gage bar 386 (Figs. 10 and 11) is also preferably adjustable. As shown, gage bar 386 is provided with bearings for a shaft 444 carrying a pair of pinions 442 each meshing with a stationary rack 440. Shaft 444 is provided with a hand wheel 446 by the rotation of which

the gage may be adjusted. A pair of clamp bolts 448 are carried by the gage bar and have slotted connection with the frame of the machine so that the gage bar may be clamped in adjusted position. The relation of the work to gage bar 386 is clearly shown in Figs. 4 and 6.

If desired, the machine may be arranged to insert staples instead of loose nails in which case the raceway may comprise a single bar 450 down which the staples may slide, as illustrated in cross-section in Fig. 12.

To assist in holding the work upon work support 360, a supplemental work support may be provided. As shown in Figs. 1 and 2, a rod 502 is adjustably clamped in a sleeve 504 carried by column 22, this rod being provided at its right hand end with a sleeve 506 in which is adjustably clamped for vertical sliding movement a second rod 508, to the upper end of which is pivoted a lever 510 having a horizontal rod 512 clamped to its upper end. A lug 514 formed upon the lower end of lever 510 prevents its movement to the right of the position indicated in Fig. 2. It will be apparent that if desired the lower portion of the work may be rested upon rod 512, while its upper portion is held by work support 360.

As illustrated in Fig. 1 the sliding head 28 may be brought into position over either work support 300 or work support 302 according as the exigencies of the situation require. It will be noted, moreover, that the machine of Fig. 2 is substantially the machine of Fig. 1 with the work support 300 eliminated, and track 26 and the various drive shafts shortened, the whole being carried upon a single column. Similarly a machine might be provided having only the work support 300. Whether one machine should include both work supports or whether separate machines would be most economical in any given case, would depend upon local conditions among which the quantity of work required to be done as related to the capacity of a single machine such as that of Fig. 1, or to the capacities of a pair of machines, one provided with each kind of work support, would be of primary consideration. It is contemplated, moreover, that the number of trunks which could be nailed upon a single machine having a work support such as 302, as illustrated in Fig. 2, would be substantially greater than that of a machine having only work support 300 owing to the smaller amount of work in each trunk of a character to be done upon that type of work support. Accordingly a single machine, as shown in Fig. 2, might well take care of the work from two machines each provided only with a work support of the character shown at 300.

In the operation of the machine the work

is placed upon one of the work supports and, by depression of the treadle, clamped in position against the gage bar or abutment 384 or 386, as the case may be. At this time 5 the head 28 is at the left hand end of its path of movement where it is held by stop 155, and clutch 178 is inoperative. When 10 the work has been thus positioned the operative shifts the rod 216 to the left, thus rendering the clutch operative and starting 15 the traversing movement of the head 28 to the right as well as the operation of the fastening inserting instrumentalities. Stop 218 being properly adjusted, when finger 220 contacts therewith rod 216 is shifted to 20 the right to throw the clutch out of operation, thus stopping the movement of the head to the right and terminating the insertion of fastenings whereupon weight 154 causes the head to travel to the left until 25 brought to rest by stop 155.

If it is desired at any time to move the head to the right without inserting fastenings, as for example preparatory to an adjustment of stop 155, this may be accomplished manually after operating lever 150 to disconnect clutch 142, 144.

The spacing of the fastenings may be varied by sliding yoke 246 upon shaft 240 bringing the idler gear 250 into engagement with one or another of the different gear members of the cone-gear 252. Since this adjustment correspondingly changes the speed of the traversing movement of the head but does not affect the number of fastenings inserted in a given interval of time, it results in a variation in the spacing of the fastenings. When the spacing of the fastenings is thus changed link 100 should be correspondingly adjusted through its bolt and slot connection to lever 98 so that the compensating rocking movement of the throat of the driver will correspond with the velocity of the traversing movement of head 28. Thus, as the sliding head is speeded up, the angular movement of the swinging head is correspondingly changed without, however, any change in the operation of the fastening inserting means.

Having described my invention, what I claim as new and desire to secure by Letters Patent of the United States is:

1. A fastening inserting machine having a head, a hopper carried by the head, fastening inserting instrumentalities also carried by the head, a work support, means for causing relative rectilinear movement of the head and the work on the work support, means for conducting fastenings from the hopper to the fastening inserting instrumentalities, and means for operating the fastening inserting instrumentalities to insert fastenings in the work during the relative movement of the head and the work.

2. A nail inserting machine having a mov-

able head, a nail hopper carried by the head, nail inserting instrumentalities also carried by the head, a work support, means for effecting relative rectilinear movement of the head and the work, means for conducting nails from the hopper to the nail inserting instrumentalities, and means for operating said nail inserting instrumentalities to insert nails in the work during said relative movement of the head and the work on the work support.

3. A fastening inserting machine having a head, a source of supply of loose fastenings carried by the head, fastening inserted instrumentalities also carried by the head, 70 a work support, means for conducting loose fastenings from the source of supply to the fastening inserting instrumentalities, means for causing relative rectilinear movement of the head and the work support, and means for operating the fastening inserting instrumentalities to insert fastenings in the work during the said relative movement of the head and the work support.

4. A fastening inserting machine having, 90 in combination, a head, a source of supply of fastenings carried by said head, a driver also carried by the head, means for transferring fastenings from the source of supply and presenting them in the path of movement of the driver, a work support, and gearing arranged to cause relative rectilinear movement of the head and the work on the work support and to operate the driver to insert fastenings during said relative movement.

5. A fastening inserting machine having a head arranged for continuous rectilinear movement throughout an operation upon a work piece presented to the machine, fastening inserting instrumentalities carried by the head, arranged to insert separate and disconnected fastenings, and means for operating said instrumentalities to insert a series of separate fastenings in the work during 100 said continuous rectilinear movement of the head.

6. A fastening inserting machine having a head, a hopper constituting a source of supply of fastenings continuously associated with the head, power operated gearing for moving the head continuously in one direction, a driver carried by the head, means for conducting fastenings from the hopper into alignment with the driver, and gearing arranged to operate the driver to insert fastenings in the work during the movement of the continuously moving head.

7. A fastening inserting machine having a head, power operated means for giving the head a continuous uniform rectilinear movement in one direction, fastening inserting instrumentalities including a throat carried by the head, and gearing arranged to operate the fastening inserting instrumentalities 125 130

to insert a succession of fastenings through the throat into the work during the rectilinear movement of the head.

8. A fastening inserting machine having a head, fastening inserting instrumentalities carried by the head, a work support, means for causing relative movement of the head and the work support, and means for moving the fastening inserting instrumentalities relatively to the head in a direction opposite to that of the relative movement of the head and the work support to compensate for the relative movement of the head and the work support during the insertion of each fastening.

9. A fastening inserting machine having a head, fastening inserting instrumentalities carried by the head, a work support, means for causing continuous relative movement of the head and the work on the work support, and means for moving the fastening inserting instrumentalities to compensate for the relative movement of the head and the work during the insertion of each fastening.

10. A fastening inserting machine comprising a work support arranged to support a bulky object during the insertion of fastenings therein, a head operable to traverse the work in a right line at a uniform rate, and fastening inserting instrumentalities carried thereby and operative to insert a series of separate and disconnected fastenings in the work during the uniform traversing movement of the head.

11. A fastening inserting machine having a head, fastening inserting instrumentalities carried by the head, a work support, means for causing continuous relative movement of the head and the work on the support, and means for moving the fastening inserting instrumentalities in a direction and at a speed to counteract said continuous relative movement of the head and the work during the insertion of each fastening.

12. A fastening inserting machine having a head, fastening inserting instrumentalities carried by the head, a work support, means for causing continuous, uniform, relative movement of the head and the work support, and means for moving the fastening inserting instrumentalities relatively to the head in a direction and at a speed to counteract the relative movement of the head and the work support during the insertion of each fastening.

13. A fastening inserting machine having a continuously moving head, fastening inserting instrumentalities including a fastening guiding throat carried by the head and arranged to insert fastenings in a stationary work piece during movement of the head, and means arranged to compensate for the movement of the continuously mov-

ing head constructed and arranged to prevent relative movement of the work and the throat during the insertion of fastenings.

14. A fastening inserting machine having a continuously moving head, fastening inserting instrumentalities including a driver carried by the head and arranged to insert fastenings in a stationary work piece during the movement of the head, and means arranged to compensate for the relative movement of the continuously moving head and the work to prevent relative movement of the work and the driver, other than substantially at right angles to the surface of the work, during the insertion of fastenings.

15. A fastening inserting machine having a continuously moving head, fastening inserting instrumentalities including a throat carried by the head, and means for moving the throat relatively to the head at an equal speed but in the opposite direction to the movement of the head during the insertion of each fastening.

16. A fastening inserting machine having a continuously moving head, a second head carried thereby, a driver carried by the second head, means for moving the second head arranged to give the driver a movement equal in extent but opposite in direction to the movement of the continuously moving head during the fastening inserting movement of the driver.

17. A fastening inserting machine having a continuously moving head, a second head carried thereby, fastening inserting instrumentalities including a throat carried by the second head, and means for moving the second head relatively to the continuously moving head arranged to give the throat a movement equal in extent but opposite in direction to the movement of the continuously moving head during the insertion of fastenings.

18. A fastening inserting machine having a driver, a driver carrying head having a continuous bodily movement, mechanism for giving the driver a fastening inserting movement, and mechanism for simultaneously rocking the driver about an axis substantially at right angles to the direction of its fastening inserting movement and opposite to the bodily movement of the head.

19. A fastening inserting machine having a straight track, a head mounted thereon, gearing arranged to move the head continuously along the track, a source of supply of fastenings carried by the head, a nozzle carried by the head, a raceway to conduct the fastenings from the source of supply to the nozzle, and a driver arranged for reciprocation through the nozzle to insert a series of fastenings in the work during the continuous movement of the head along the track.

20. A fastening inserting machine comprising a work support, a head, fastening inserting means carried thereby having a nozzle, means for causing continuous rectilinear movement of the head relatively to the work support, means for operating the fastening inserting means to cause the insertion of a series of fastenings through the nozzle into the work upon the work support during the continuous movement of the head, and means for preventing relative movement of the nozzle and the work support during the fastening inserting operations. 65
- 5 21. A fastening inserting machine having a continuously moving head, a driver carried by the head, and means for moving the driver relatively to the head at an equal speed but in the opposite direction from the movement of the head during its fastening inserting movement. 70
- 10 22. A fastening inserting machine having a continuously moving head, a swinging head carried thereby, a driver carried by the swinging head, and means for swinging the swinging head arranged to give the driver a movement relative to the first named head equal in extent but opposite in direction to the movement thereof during the fastening inserting movement of the driver. 75
- 20 23. A fastening inserting machine comprising a stationary work support, a head, a source of fastening supply carried by the head, means for causing continuous movement of the head along the work support, a driver carried by the head, and means for giving the driver a movement transverse to its fastening inserting movement and simultaneous therewith in such a direction and of such velocity as to counteract the movement of the head along the work support during the insertion of fastenings in the work. 80
- 30 24. A fastening inserting machine comprising a work support arranged to support a bulky object during the insertion of fastenings therein, a head arranged to traverse the work, and fastening inserting instrumentalities carried thereby and operative to insert a series of fastenings in the work during the traversing movement of the head, said fastening inserting instrumentalities including a driver and driver reciprocating mechanism, and means for giving the driver a movement relative to the head equal in extent but opposite in direction to the movement of the head during its fastening inserting movement. 85
- 40 25. A fastening inserting machine having a continuously moving head, fastening inserting instrumentalities carried by the head operated at a constant rate of speed arranged to insert in the work a succession of separate and disconnected fastenings, and gear shift mechanism arranged to vary the speed of the movement of the head without varying the rate of insertion of the fastenings and thus to vary the spacing of the fastenings inserted in the work. 90
- 50 26. A fastening inserting machine having a continuously moving head, fastening inserting instrumentalities carried by the head and arranged to insert fastenings successively in the work, and gear shift mechanism comprising a driving gear, a group of driven gears and a gear driven from the driving gear and movable into driving engagement with any one of the group of driven gears arranged to vary the distance the head moves in the time-interval between the insertion of successive fastenings, thereby varying the spacing of the fastenings inserted in the work. 95
- 60 27. A fastening inserting machine having a continuously moving head, a throat and driver carried by the head and arranged to insert fastenings in the work, operating means for the driver arranged to operate at a constant speed, and gear shift mechanism arranged to control the velocity of movement of the head and thus to vary the spacing of the fastenings inserted. 100
- 70 28. A fastening inserting machine having a continuously moving head, fastening inserting instrumentalities including a throat and driver carried by the head, means for moving the throat at an equal speed but in the opposite direction from the movement of the head during the insertion of fastenings, and means for varying the velocity of movement of the head to vary the spacing of the fastenings inserted in the work. 105
- 80 29. A fastening inserting machine having a continuously moving head, a second head carried thereby, fastening inserting instrumentalities carried by the second head, means for operating the fastening inserting instrumentalities at a uniform velocity, means for moving the second head relatively to the continuously moving head arranged to give the fastening inserting instrumentalities movement equal in extent but opposite in direction to the movement of the continuously moving head during the insertion of fastenings, and means for varying the speed of the continuously moving head to vary the spacing of the fastenings in the work. 110
- 90 30. A fastening inserting machine having a head arranged for rectilinear movement transversely of the work, fastening inserting instrumentalities carried by the head and operated to insert fastenings at a constant rate in work presented thereto, gearing for causing movement of the head transversely of the work, and manually operated gear shift mechanism arranged to vary the rate of speed of the head relatively to the rate of fastening insertion and thus to vary the spacing of the fastenings inserted in the work. 115
- 100 31. A fastening inserting machine having a head arranged for rectilinear movement transversely of the work, fastening inserting instrumentalities carried by the head and operated to insert fastenings at a constant rate in work presented thereto, gearing for causing movement of the head transversely of the work, and manually operated gear shift mechanism arranged to vary the rate of speed of the head relatively to the rate of fastening insertion and thus to vary the spacing of the fastenings inserted in the work. 120
- 110 32. A fastening inserting machine having a head arranged for rectilinear movement transversely of the work, fastening inserting instrumentalities carried by the head and operated to insert fastenings at a constant rate in work presented thereto, gearing for causing movement of the head transversely of the work, and manually operated gear shift mechanism arranged to vary the rate of speed of the head relatively to the rate of fastening insertion and thus to vary the spacing of the fastenings inserted in the work. 125

spacing of the fastenings inserted in the work.

31. A fastening inserting machine having a head, fastening inserting instrumentalities carried by the head, a work support, gearing arranged to cause relative continuous rectilinear movement of the work support and work transversely of the head, operating means for the fastening inserting instrumentalities arranged to cause the insertion of fastenings during said rectilinear movement and to cause the cessation of the insertion of fastenings as soon as said rectilinear movement ends, and gear shift mechanism arranged to vary the speed of said continuous relative movement and thus to vary the spacing of the fastenings inserted in the work.

32. A fastening inserting machine having a head, fastening inserting instrumentalities carried thereby and arranged to drive separate and disconnected fastenings into the work, gearing arranged to cause continuous movement of the head transversely of the work as the fastenings are inserted, and gear shift mechanism arranged to vary the speed of said continuous movement without affecting the number of fastenings inserted in a given unit of time.

33. A fastening inserting machine having a frame, a head mounted for traversing movement thereon, a nail hopper and nail inserting means carried by the head, a clutch, gearing operatively connected to the clutch and arranged to cause traversing movement of the head in one direction, a pair of stops one arranged to disconnect the clutch as the head reaches one end of its path of movement and the other arranged to stop the head as the head reaches the other end of its path of movement, and means for causing cessation of the insertion of nails as the head moves in one direction.

34. A nail inserting machine having a frame, a head mounted for traversing movement thereon, nail inserting means comprising a throat and a driver and operating means therefor carried by the head, a clutch, gearing operatively connected to the clutch and arranged to cause traversing movement of the head in one direction, and a weight connected to the head and arranged to cause traversing movement of the head in the other direction when the clutch is disconnected.

35. A fastening inserting machine having a straight track, a plurality of drive shafts parallel thereto, a head mounted for travel thereon, fastening inserting means carried by the head and operated from one of said drive shafts, gearing including a clutch arranged to move the head along the track in one direction operated from another of said drive shafts, a stop adjacent to the track and arranged to disconnect the clutch to permit the movement of the head along the

track in the other direction, and means for moving the head along the track in said last-named direction when the clutch is disconnected.

36. A fastening inserting machine having a track, a head carried thereby, means for driving separate fastenings carried by the head, gearing including a clutch arranged to move the head continuously along the track in one direction as the fastenings are driven, a stop adjacent to the track and arranged to disconnect the clutch to permit the movement of the head along the track in the other direction, means for causing the cessation of the driving of fastenings as the clutch is disconnected, and a weight for moving the head along the track in said last-named direction when the clutch is disconnected.

37. A fastening inserting machine having a track, a head mounted thereon, gearing arranged to cause the head to travel along the track and including a clutch, a stop adjacent to the track arranged to shift the clutch and thereby to reverse the direction of movement of the head, and a driver carried by the head and arranged to drive fastenings into the work while the head is moving along the track.

38. A fastening inserting machine having a track, a head mounted thereon, a driver carried by the head and arranged to drive fastenings into the work during the movement of the head along the track, a continuously rotated shaft adjacent to the track, gearing driven from the shaft and operative to move the head continuously along the track, and a stop adjacent to the track and arranged to shift said gearing and thus to reverse the direction of movement of the head.

39. A work support having an upwardly extending portion, a forwardly extending portion, and a bearing portion having an axis extending in the direction of the work engaging portion of the work support, the whole being formed and arranged so that rotation of the work support about the axis of the bearing portion causes the previously upstanding portion to extend forwardly and the previously forwardly extending portion to extend upwardly.

40. A work support comprising a work engaging head and a member having an upwardly extending portion, a forwardly extending portion, and a bearing portion having an axis passing through the head formed and arranged so that rotation of the work support about the axis of the bearing portion causes the previously upstanding portion to extend forwardly and the previously forwardly extending portion to extend upwardly without disturbing the position of the work engaging head.

41. A work support comprising a bar arranged to enter a dihedral angle of the

work, and a pair of supports for said bar each having an upwardly extending portion, a forwardly extending portion and a bearing portion, and gearing for rotating each of the supports about the axis of its bearing portion.

42. A work support comprising a bar arranged to enter a dihedral angle of the work, and a pair of supports for said bar each comprising a rod having an upwardly extending portion, a forwardly extending portion, and a bearing portion, and means for simultaneously rotating said rods in opposite directions about the axis of said bearing portion.

43. A work support having a substantially horizontal portion, a substantially vertical portion, and a bearing portion arranged at substantially 45° to one of said previously-named portions so that rotation of the work support about the axis of the bearing portion through one-half a revolution will cause the previously substantially vertical portion to become substantially horizontal and the previously substantially horizontal portion to become substantially vertical.

44. A work support comprising a work engaging member and an arm carrying the work engaging member having a substantially horizontal portion, a substantially vertical portion, and a bearing portion arranged on an axis at substantially 45° to one of said previously-named portions and extending in the direction of the work engaging member so that rotation of the work support about the axis of the bearing portion through one-half a revolution will cause the previously substantially vertical portion to become substantially horizontal and the previously substantially horizontal portion to become substantially vertical.

45. A work support comprising a rod having an approximately horizontal portion, an approximately vertical portion, and a bearing portion having an axis arranged at approximately 45° to one of said previously-named portions, a bearing for said portion having an axis extending in the direction of the end of said rod so that rotation of the rod in the bearing through one-half a revolution causes the previously approximately vertical portion to become approximately horizontal and the previously approximately horizontal portion to become approximately vertical without changing the position of the end of the rod, and means for rotating the rod in said bearing.

46. A work support comprising a bar arranged to enter a dihedral angle of the work, and a pair of supports for said bar each having a substantially horizontal portion, a substantially vertical portion, a bearing portion arranged at substantially 45° to one of the previously-named portions, and means for

rotating each of the supports through half a revolution.

47. A work support comprising a bar arranged to enter a dihedral angle of the work, a pair of supports for said bar each having a substantially horizontal portion, a substantially vertical portion, and a bearing arranged on an axis at substantially 45° to one of the previously-named portions, means for rotating each of the supports through half a revolution, and a vertically adjustable member remote from said bar and arranged to co-operate therewith in supporting the work.

48. A work support comprising a rod arranged to support the work, a bearing member in which the rod is mounted for rotation, a horizontal shaft upon which the bearing member is mounted, a stop arranged to limit the movement of the bearing member about said shaft, a spring tending to move the bearing member into engagement with the stop, and means for raising the work support without disengaging the stop and the bearing member.

49. A work support comprising a rod arranged to support the work, a bearing member in which the rod is mounted for axial rotation, a horizontal shaft upon which the bearing member is mounted, a stop arranged to limit the movement of the bearing member about said shaft, a spring tending to move the bearing member into engagement with the stop, and a counterweight carried by the end of the rod remote from the work.

50. A work support comprising a work sustaining rod having an approximately horizontal portion, an approximately vertical portion and a bearing portion having an axis arranged at an angle of approximately 45° to one of said previously-named portions so that rotation of the work support about the axis of said bearing portion through one-half a revolution causes the previously approximately vertical portion to become approximately horizontal and the previously approximately horizontal portion to become approximately vertical, a bearing member for the bearing portion, and mechanism for raising and lowering the bearing member to present the work to and withdraw it from the machine.

51. A work support comprising a bar arranged to enter a dihedral angle of the work, a pair of rods carrying said bar and each having an approximately horizontal portion, an approximately vertical portion, and a bearing portion arranged at approximately 45° to one of said previously-named portions, a pair of bearing members in which the bearing portion of said rods are mounted, and gearing arranged to rotate said rods in said bearing members.

52. A work support comprising a bar ar-

ranged to enter a dihedral angle of the work, a pair of rods carrying said bar and each having an approximately horizontal portion, an approximately vertical portion, 5 and a bearing portion arranged at approximately 45° to one of said previously-named portions, a pair of bearing members in which the bearing portion of said rods are mounted, and gearing arranged to rotate 10 said rods simultaneously in opposite directions in said bearings.

53. A work support comprising a bar arranged to enter a dihedral angle of the work, a pair of rods carrying said bar and each 15 having an approximately horizontal portion, an approximately vertical portion, and a bearing portion arranged at approximately 45° to one of said previously-named portions, a pair of bearing members in which 20 the bearing portion of said rods are mounted, a manually operable lever, and connections from the lever to the rods constructed and arranged so that swinging of the lever causes 25 simultaneous rotation of the two rods in opposite directions in said bearings.

54. A work support comprising a bar arranged to enter a dihedral angle of the work and a pair of supports for said bar each comprising a rod having an approximately 30 horizontal portion, an approximately vertical portion, and a bearing portion arranged at approximately 45° to one of the previously named portions, and means for simultaneously rotating said rods in opposite directions through half a revolution. 35

55. A work support comprising a rod having an approximately horizontal portion, an approximately vertical portion, and a bearing portion having an axis arranged at approximately 40 45° to one of said previously named portions, a bearing for said bearing portion arranged so that rotation of the rod in the bearing through one-half a revolution causes the previously approximately vertical portion to become approximately horizontal and the previously approximately horizontal portion to become approximately vertical, 45 and means for rotating the rod in said bearing.

56. A machine of the class described having, in combination, an abutment and a work support arranged to press the work against the abutment during the performance of an 55 operation thereon comprising a rod, a bearing member for the rod, a shaft upon which the bearing member is mounted, an inner slide carrying said shaft, an outer slide carrying said inner slide, mechanism for raising and lowering said outer slide, a spring 60 connection between the two slides arranged to cause the raising of the outer slide to raise the inner slide until the work carried upon the work support engages the abutment and thereafter to yield, and a member carried by 65 the outer slide and arranged to engage the

inner slide to cause the lowering of the outer slide positively to lower the inner slide and the work support.

57. Gage mechanism comprising a gage member having two working positions, a 70 rack connected thereto, a gear segment engaging the rack and carrying a pair of seats, a shaft upon which the gear segment is mounted, a lever for rocking the shaft, and a pair of adjustable stops arranged alternatively to engage the respective seats to limit the rocking movement of the gear segment and shaft in both directions, each stop 75 acting to position the gage in one of its working positions. 80

58. Gage mechanism comprising a gage member having two working positions, a rack connected thereto, a gear segment engaging the rack and carrying a pair of seats, a shaft upon which the gear segment is 85 mounted, a lever for rocking the shaft, a pair of stop members arranged for arcuate adjustment alternatively to engage the respective seats to limit the rocking movement of the gear segment and shaft in both directions, and a spring connected to the gear segment and tending to move and hold the gear segment and shaft in engagement with either 90 of the stops to hold the gage in one of its working positions. 95

59. Gage mechanism comprising an elongated adjustable gage member against which work may be positioned, and means for shifting said gage member comprising a 100 rack bar attached to each end thereof, a gear segment engaging each rack bar, a shaft upon which the gear segments are mounted, a lever for rocking the shaft, and a pair of adjustable stops arranged to limit the movement of the shaft and gear segments as the 105 gage is shifted.

60. Gage mechanism comprising an elongated adjustable gage member against which work may be positioned, and means for shifting said gage member comprising a rack bar 110 attached to each end thereof, a gear segment engaging each rack bar, a shaft upon which the gear segments are mounted, a hand lever for rocking the shaft, a pair of adjustable stops arranged to limit the movement of the shaft and segments as the gage is shifted, and a spring arranged to hold the shaft and segments against either stop and tending to 115 complete the movement of the gage after its movement has been started by rocking the 120 shaft through a small angle.

61. Gage mechanism comprising a gage member having two operative positions, a shaft, a segment mounted on the shaft, connections from the segment to the gage member arranged to cause rocking of the segment to shift the gage member from one operative position to another, means for rocking the shaft, a pair of stops arranged to limit the movement of the shaft as it is rocked in 125 130

either direction, and a spring tending to move and hold the shaft and segment in engagement with either of the stops as it is rocked towards that stop and to hold the gage in either operative position.

62. A gage comprising a work engaging member having a socket formed therein, a spring plunger arranged to enter said socket,

a second socket arranged at right angles to the first, and a pin entering said second socket pivotally mounted for movement about an axis at right angles thereto.

In testimony whereof I have signed my name to this specification.

GEORGE GODDU.
